CLAIM

I claim the ornamental design for a bank of modular gaming machines with curved displays, as shown and described.

DESCRIPTION

FIG. 1 is a perspective view of a first embodiment of a bank of modular gaming machines with curved displays in accordance with the new design;

FIG. 2 is a front side view of the bank of modular gaming machines with curved displays shown in FIG. 1.

FIG. 3 is a top view of the bank of modular gaming machines with curved displays shown in FIG. 1.

FIG. 4 is a perspective view of a second embodiment of the bank of modular gaming machines with curved displays;

FIG. 5 is a front side view of the bank of modular gaming machines with curved displays shown in FIG. 4.

FIG. 6 is a top view of the bank of modular gaming machines with curved displays shown in FIG. 4.

FIG. 7 is a perspective view of a third embodiment of the bank of modular gaming machines with curved displays;

FIG. 8 is a front view of the bank of modular gaming machines with curved displays shown in FIG. 7; and,

FIG. 9 is a top view of the bank of modular gaming machines with curved displays shown in FIG. 7.

The broken line showing of portions of the bank of modular gaming machines with curved displays depicts environment and forms no part of the claim.
